(57) CLAIM

The ornamental design for a toy for animals, as shown and described.

DESCRIPTION

FIG. 1 is a front, left, top perspective view of a toy for animals showing my new design;

FIG. 2 is a front, top perspective view thereof;

FIG. 3 is a front elevation view thereof;

FIG. 4 is a rear elevation view thereof;

FIG. 5 is a right-side elevation view thereof;

FIG. 6 is a left side elevation view thereof;

FIG. 7 is a top plan view thereof; and,

FIG. 8 is a bottom plan view thereof.

The dashed broken lines illustrate portions of the toy for animals that form no part of the claimed design, and the dot-dash broken lines depict environmental structure that form no part of the claimed design.

1 Claim, 7 Drawing Sheets
